DESIGN FOR A BRACELET

Joseph Balme, Paris, France

Application January 31, 1938, Serial No. 74,730

Term of patent 3½ years

To all whom it may concern:

Be it known that, Joseph Balme, a citizen of the Republic of France, residing at Paris, in the Department of Seine and country of France, has invented a new, original, and ornamental Design for a Bracelet, of which the following is a specification, reference being had to the accompanying drawing, forming part thereof.

The figure is a plan view of the bracelet in partly coiled position showing my new design.

The dominant feature resides in a bracelet comprising an alternate arrangement of large and small flowers, each large flower consisting of a rose having a base formed of a stem surrounded by leaves, and a pair of eyes one each extending from opposite sides of the rose in a plane substantially normal to said stem; each said flower consisting of a rose having a stemless base formed of leaves, and a pair of oppositely extending eyes pivotally engaging the eyes of a large rose, all as shown.

I claim:

The ornamental design for a bracelet, as shown and described.

JOSEPH BALME.
